LOCKING AND RELEASING MECHANISM FOR
SWINGING DOORS OR THE LIKE

Frederick C. Griswold, Port Jefferson, N. Y.

Application December 17, 1935, Serial No. 54,824

10 Claims. (Cl. 292—262)

One object of my invention is to provide simple and effective means for automatically locking a swinging element, such, as for instance, a door, window, shutter, or the like, in its open position, combined with novel manually operated means for releasing the swinging element to permit it to be closed.

Another object is to provide means for automatically locking the swinging element closed or open, combined with manually operated means for releasing the swinging element to permit it to be either opened or closed.

My invention consists, generally, in a device for locking the swinging element open, said device comprising fixed and movable locking members combined with a handle mounted on the swinging element and operatively connected to the movable locking member for rocking it to release it from the fixed locking member, to permit the closure of the swinging element, said movable locking member being mounted on the swinging element for universal movement and being slidable in the fixed locking member.

My invention also includes, in certain forms, upper latches or both upper and lower latches mounted on the swinging element for automatically locking the swinging element in its closed position, said latches being operatively connected to the said handle whereby they may be released when it is desired to open the swinging element, the handle in this instance serving both as the manually operated means for releasing the swinging element from its closed position and for releasing the swinging element from its open position.

A practical embodiment of my invention is represented in the accompanying drawings which represent my invention applied to the double swinging doors of a building structure.

Fig. 1 represents an inside elevation with the doors in their closed position.

Fig. 2 represents a horizontal section taken in the plane of the line II—II of Fig. 1, looking in the direction of the arrows.

Fig. 3 represents a similar horizontal section showing the doors locked in their open position.

Fig. 4 represents a vertical section taken in the plane of the line IV—IV of Fig. 3, looking in the direction of the arrows.

Fig. 5 represents a face view, on an enlarged scale, of the upper latch of one of the doors.

Fig. 6 represents a vertical section taken in the plane of the line VI—VI of Fig. 5, looking in the direction of the arrows.

Fig. 7 represents a face view of the manually

operated handle and its adjacent parts, the handle being shown in full lines in one position and in dotted lines in another position.

Fig. 8 represents a vertical section taken in the plane of the line VIII—VIII of Fig. 7. 5

Fig. 9 represents a face view of the lower latch.

Fig. 10 represents a vertical section taken in the plane of the line X—X of Fig. 9, looking in the direction of the arrows.

Fig. 11 represents a face view of the ball and 10 socket connection between the movable locking member and the door.

Fig. 12 represents a plan view of the same.

Fig. 13 represents a vertical section taken in the plane of the line XIII—XIII of Fig. 12, looking in the direction of the arrows. 15

Fig. 14 represents a detail angular view, partly in section, with the movable part of the ball and socket joint shown in full lines in one position and in dotted lines in another position. 20

Fig. 15 represents a detail plan view of the operating rod which rocks the movable member of the ball and socket joint.

Fig. 16 represents a side view of the fixed locking member with the movable locking member in 25 the position it occupies when the door is closed.

Fig. 17 represents an inverted plan view of the same.

Fig. 18 represents a detail view showing the movable locking member in full lines in its position for locking the door open and in dotted lines rocked to its released position. 30

The doors 1 and 2 are, in the present instance, the elements which are hinged to swing on the uprights of the frame 3 which forms the support 35 for the doors.

The door 1 may be locked in its closed position by the provision of upper and lower latches 4, 4 and the door 2 may be locked in its closed position to the door 1 by a lock 5 of any well known 40 or approved type.

The means for automatically locking one door in its open position is substantially the same as the means for automatically locking the other door in its open position and therefore only one 45 of these means will be specifically described, which means is constructed, arranged and operated as follows:

A fixed locking member is provided for each door, which fixed locking member is secured to 50 the head of the door frame about midway between the inner and outer edges of the door. The fixed locking member comprises a plate 6 having a depending looped portion consisting of two loops 7 and 8. 55

A movable locking member is provided for each door in position to coat with the fixed locking member to lock the door automatically in its open position, which movable locking member 5 comprises a horizontally disposed bar 9 mounted at one end for universal movement on the door and provided at its other end with a hooked portion. The universal mounting for the hook bar is shown in this instance as a ball and 10 socket joint, the socket member 10 being fixed to the door and the ball member 11 having a depending arm 12 in which the adjacent end of the hook bar 9 is seated. This depending arm 12 is provided with a circumferential reduced portion 15 forming a neck 13.

The hook at the other end of the bar is shaped to form a vertical portion 14, a lateral portion 15 and a return portion 16. The body of the hook bar 9 is slidably supported in the loop 7 of its 20 fixed locking member and the return portion 16 of the hook bar is adapted to enter the loop 3 of the said fixed locking member as the door nears the end of its opening movement. As the door reaches the end of this opening movement the 25 vertical portion 14 drops into locking engagement with one side of the depending looped portion of the fixed locking member and the horizontal portion 15 of the hook engages the opposite side of the loop member, the vertical and 30 horizontal portions thus forming shoulders which lock the door in its open position against lost motion.

The manually operated means for releasing the movable locking member from its fixed locking member to permit the door to be swung to its closed position is constructed, arranged and operated as follows:

A handle 17 is pivoted at 18 to the door in a convenient position for the operator. The lower 40 end of a vertically disposed operating rod 19 is pivoted eccentrically to the handle 17 and the upper end of this rod 19 is connected to a horizontally disposed operating rod 22 through the arms 20 and 21 of a bell crank lever. The other 45 end of this horizontally disposed operating rod 22 is constructed to swing the ball member 11 to rock the hook bar 9 to the position shown in dotted outline in Fig. 14 as follows:

A block 23 is carried on the operating rod 22 50 and a short bar 24 projects from this block spaced from and parallel to the rod 22 so that the neck 13 of the ball member depending arm 12 is embraced between the said rod 22 and the bar 24. The block 23 is provided with a reduced 55 edge 25 arranged to engage the neck 13 to rock the ball member 11 and thereby the hook bar 9. As the rod 22 is moved endwise in one direction by the endwise movement of the operating rod 19 due to the swinging of the handle 17, the end of 60 rod 22 carrying block 23 is caused to swing away from the inner face of the door. This movement of the rod end and block causes the lower end of the depending arm 12 to swing away from the door by rocking about the ball and socket structure. The bar 9 is caused to rock about the 65 return portion 16 of the hook by the outward swinging of arm 12. This rocking of the hook bar, because of the bearing of the return portion 16 of the hook forming a pivot in its loop 8, serves 70 to lift the bar sufficiently to move the vertical portion 14 of the hook out of its locking engagement with its loop 7 of the fixed locking member, as shown in dotted outline in Fig. 18, thereby permitting the door to be swung to its closed 75 position.

The upper and lower latches 4, 4 which automatically lock the door 1 in its closed position are operated by the handle 17 to unlock the door 1 and permit it to be swung to its open position as follows:

The uprising vertically disposed operating rod 19 is connected not only to the arm 20 of the bell crank lever 20, 21 but it is also connected to operate the upper latch 4. A depending vertically disposed operating rod 26 is eccentrically connected at its upper end to the pivoted handle 17 and at its lower end it is operatively connected to the lower latch 4 so that the swinging movement of the handle in one direction will cause the upper and lower operating rods 19 and 26 10 respectively, to withdraw the latches 4, 4 from their locking positions. Springs 27, 27 are provided for yieldingly pressing the latches to their locking positions.

It is evident that various changes may be resorted to in the construction, form and arrangement of the several parts without departing from the spirit and scope of my invention, and hence I do not intend to be limited to the particular embodiment herein shown and described, but 20

What I claim is:

1. In a support with an element hinged to swing thereon; a fixed locking member provided with two loops, a hook bar mounted for universal movement on the swinging member and having one part slidable and rotatable in one loop and another part slidable in the other loop for automatically locking the hook bar to the fixed member when the swinging element is open, and manually operated means for rocking the hook bar axially in said last named loop to release it from its locking engagement with the fixed member. 30

2. In a support with an element hinged to swing thereon, a fixed locking member provided with two loops, a hook bar mounted for universal movement on the swinging member and having one part slidable and rotatable in one loop and another part slidable in the other loop for automatically locking the hook bar to the fixed member when the swinging element is open, and manually operated means for rocking the hook bar axially in said last named loop to release it 40 from its locking engagement with the fixed member, 45 said hook bar being shaped to prevent lost motion when locked to the fixed member. 50

3. In a support with an element hinged to swing thereon, a fixed locking member having abutments depending from said support, a bar mounted at one end for universal movement on the swinging element and the other end provided with a return portion forming a hook, the bar and its return portion being slidable in the fixed member, said hook bar having shoulders adjacent the return portion adapted to automatically engage opposite abutments on the fixed locking member as the element is swung to its open position to lock the element, and manually operated means for rocking the hook bar axially on the said return portion in the fixed locking member to release the shoulders from their engagement with the abutments on the fixed locking member. 55 60 65

4. In a support with an element hinged to swing thereon, a fixed locking member having a looped portion depending from said support, a bar mounted at one end for universal movement on the swinging element and the other end provided with a return portion forming a hook, the bar and its return portion being slidable in the 70 75 75

looped portion, said hook bar having shoulders adjacent its return portion adapted to automatically engage the opposite sides of the looped portion as the element is swung to its open position 5 to lock the element, and manually operated means for rocking the hook bar axially on the said return portion in the looped portion to release the shoulders from their locking engagement with the looped portion of the fixed locking member.

5. In a support with an element hinged to swing thereon, a fixed locking member having two loops juxtaposed and depending from said support, a bar mounted at one end for universal 15 movement on the swinging element and the other end provided with a return portion forming a hook, the bar being slidable in one of said loops and its return portion disposed to slide into and out of the other loop, said hook bar having shoulders adjacent the return portion adapted to automatically engage the opposite sides of the loops as the element is swung to its open position to lock the element, and manually operated means for rocking the hook bar axially on the said return portion in the last named loop to release the shoulders from their locking engagement with the loops of the fixed locking member.

6. In a support with an element hinged to swing thereon, a fixed locking member, a movable locking member, a ball and socket joint on the swinging element for the movable locking member, and manually operated means mounted on the swinging element for rocking the movable locking member and comprising a handle, a vertically disposed rod moved endwise on the swinging element by said handle, a horizontally disposed rod having a rock lever connection with the vertically disposed rod and positioned to engage the movable part of said ball and socket joint.

40 7. In a device comprising a support, an element hinged to swing thereon, and an upper locking device carried by the swinging element for locking it closed, the combination of a fixed locking member on the support, a ball and socket joint 45 carried by the swinging element, a bar having one end connected to oscillate with said ball and socket joint and arranged to slidably engage the fixed locking member, a rod connecting the locking device and ball and socket joint, and a manually operated means for simultaneously 50 moving the locking device vertically and said rod horizontally to actuate the ball and socket joint which in turn oscillates the bar and releases it from the fixed locking member.

55 8. In a device comprising a support, an element hinged to swing thereon, and an upper locking device carried by the swinging element for locking it closed, the combination of a fixed locking member on the support, a ball and socket joint carried by the swinging element, a bar having one 60 end connected to said ball and socket joint and

oscillated by the movement of said joint, the other end of said bar being provided with a hook arranged to engage the fixed locking member for locking the element open and slidable in the locking member when the hook is released, a horizontally disposed rod interposed between the locking device and the ball and socket joint, and a manually operated means for simultaneously moving the locking device vertically and said rod longitudinally to actuate the ball and socket joint 10 which in turn oscillates the bar and releases the hook from the fixed locking member.

9. In a device comprising a support, an element hinged to swing thereon, and an upper locking device carried by the swinging element for locking it closed, the combination of a fixed locking member on the support, a ball and socket joint carried by the swinging element, a bar having one end connected to said ball and socket joint and oscillated by the movement of said joint, the other end of said bar being provided with a hook arranged to engage the fixed locking member for locking the element open and slidable in the locking member when the hook is released, a horizontally disposed rod interposed between the locking device and the ball and socket joint, said rod having a lost motion connection with the ball and socket joint, and a manually operated means for simultaneously moving the locking device vertically and said rod longitudinally to actuate the ball and socket joint 20 which in turn oscillates the bar and releases the hook from the fixed locking member.

10. In a device comprising a support, an element hinged to swing thereon, and an upper locking device carried by the swinging element for locking it closed, the combination of a fixed locking member on the support, a ball and socket joint carried by the swinging element, a bar having one end connected to said ball and socket joint and oscillated by the movement of said joint, the other end of said bar being provided with a hook arranged to engage the fixed locking member for locking the element open and slidable in the locking member when the hook is released, a horizontally disposed rod interposed between the locking device and the ball and socket joint, said rod having a lost motion connection with the ball and socket joint, and a manually operated means for simultaneously moving the locking device vertically and said rod longitudinally to actuate the ball and socket joint 30 which in turn oscillates the bar and releases the hook from the fixed locking member.

35 11. In a device comprising a support, an element hinged to swing thereon, and an upper locking device carried by the swinging element for locking it closed, the combination of a fixed locking member on the support, a ball and socket joint carried by the swinging element, a bar having one end connected to said ball and socket joint and oscillated by the movement of said joint, the other end of said bar being provided with a hook arranged to engage the fixed locking member for locking the element open and slidable in the locking member when the hook is released, a horizontally disposed rod interposed between the locking device and the ball and socket joint, said rod having a lost motion connection with the ball and socket joint, and a manually operated means for simultaneously moving the locking device vertically and said rod longitudinally to actuate the ball and socket joint 40 which in turn oscillates the bar and releases the hook from the fixed locking member.

45 12. In a device comprising a support, an element hinged to swing thereon, and an upper locking device carried by the swinging element for locking it closed, the combination of a fixed locking member on the support, a ball and socket joint carried by the swinging element, a bar having one end connected to said ball and socket joint and oscillated by the movement of said joint, the other end of said bar being provided with a hook arranged to engage the fixed locking member for locking the element open and slidable in the locking member when the hook is released, a horizontally disposed rod interposed between the locking device and the ball and socket joint, said rod having a lost motion connection with the ball and socket joint, and a manually operated means for simultaneously moving the locking device vertically and said rod longitudinally to actuate the ball and socket joint 50 which in turn oscillates the bar and releases the hook from the fixed locking member.

55 13. In a device comprising a support, an element hinged to swing thereon, and an upper locking device carried by the swinging element for locking it closed, the combination of a fixed locking member on the support, a ball and socket joint carried by the swinging element, a bar having one end connected to said ball and socket joint and oscillated by the movement of said joint, the other end of said bar being provided with a hook arranged to engage the fixed locking member for locking the element open and slidable in the locking member when the hook is released, a horizontally disposed rod interposed between the locking device and the ball and socket joint, said rod having a lost motion connection with the ball and socket joint, and a manually operated means for simultaneously moving the locking device vertically and said rod longitudinally to actuate the ball and socket joint 60 which in turn oscillates the bar and releases the hook from the fixed locking member.

FREDERICK C. GRISWOLD.
